WEATHER STRIP

Joseph F. Fauner, Irvington, N. J.

Application June 23, 1937, Serial No. 149,878

2 Claims. (Cl. 20—69)

This invention relates to weather strips in general, and particularly to what may be termed self-locking and self-guiding resilient weather strips.

5 The prime object of the present invention is to provide a weather strip construction which not only cooperates with, but combines and connects the frame and a closure therefor, to which the structure is secured, but which will effectively 10 prevent any leakage between the two objects, and which will be practically immune to detrimental effects to its purpose of weather tightening caused by either shrinkage or swelling of the frame or closure or both, as is usually the case 15 in heretofore designed weather stripping.

Another object of the present invention is to so construct and arrange the various parts of the device as to constantly keep them under tension, thereby providing a perfect contact and 20 consequent seal between the objects equipped with my device.

A still further object of my invention is to provide in a weather strip construction male and female members in which the male member takes 25 substantially the shape of a coiled-up, substantially spiral structure in which each bent portion is spaced from the other so as to render the entire construction resilient.

Another object of my invention is to so construct and arrange the female member of my 30 structure that the latter in itself is resilient throughout, starting from the place of fixed attachment, to either the frame or the closure, and in which a longitudinal pocket formation is provided for resiliently accommodating the cooperating male member.

A still further object of my invention is to construct the pocket-like structure of the female member so that it comprises a plurality of individual surfaces bent in different places, but in 40 which each of the surfaces is spaced from the adjacent surface and in which a reinforcement is provided which serves as limiting means for a possible sidewise motion of the male member.

45 A still further object of my invention is to cushion the pocket-like structure of the female member either by providing a resilient extension therefrom, forming an integral part thereof, or by associating with the bottom portion of the 50 female member independent, resilient means in the form of a corrugated resilient strip, all for the purpose of rendering the pocket-like structure of the female member more resilient.

The foregoing and still further objects of my 55 invention will become more fully apparent from

the following description and the accompanying drawing, in which are illustrated a few preferred forms of my invention, but which drawing is not intended to limit me to the exact construction shown, and in which

5 Fig. 1 is a typical cross-sectional view through a frame and a closure, such as a sash, slidably mounted in the frame;

Fig. 2 is a partial front elevation of the female member with the sash removed;

Fig. 3 is a typical cross-sectional view of a male member;

Fig. 4 is an enlarged cross-sectional view of a female member similar to that shown in Fig. 1;

Fig. 5 is a cross-sectional view through a modified form of a female member;

Fig. 6 is a cross-sectional view of a still other modification of a female member;

Fig. 7 is a typical cross-sectional view of a modified form of a male member;

20 Figs. 8 and 9 are modified forms of female members for accommodating the male member shown in Fig. 7; and

Figs. 10, 11 and 12 illustrate diagrammatical views of my weather strip structure provided with 25 auxiliary, resilient means secured beneath the pocket-like structure of the female members.

25 Referring now specifically to the figures, in Fig. 1 there will be seen a portion of a frame 10, equipped with parting strips and moldings such as shown at 11 and 12, between which slidably 30 operates a closure or sash 13. Secured to frame 10 and below either the molding or the parting strip, but in this case below molding 12, there is attached at 14 a resiliently mounted female member 15, such as shown in detail in Fig. 4. In interengagement with female member 15 and secured to a cut-out corner of sash 13 is a male member 16, the construction of which is clearly 35 illustrated in Fig. 3.

40 Offset from the attaching portion of female member 15, I preferably provide a horizontal portion 17 (see Fig. 4), at the other end of which there is formed a reinforcing and limiting rib 18, which forms a lock for the male member 16. 45 Extending from the rib, there is a horizontal portion 19, terminating in a semi-loop 20, from which the material is turned upon itself at 21. At the other end of this member, there is provided an offset 22 from which extends towards 50 rib 18 an outer portion 23, which terminates in a bend 24, from which the material is turned inwards into a contacting face 25.

55 In this way a pocket is formed between rib 18 and outer surface 23, and end portion 25, into

which male member 16 is inserted. The male member comprises an upright portion which is bent substantially at right angles at 26, from which bend extends a horizontal portion 27, a downwardly bent vertical portion 28, another horizontal outer portion 29, an upward short portion 30, and an inner contacting portion 31. The latter is intended to engage the inner portion 25 of the female member.

10 In Figs. 3, 4, 5 and 6, the contacting portions are illustrated to represent straight surfaces in full lines. The broken lines, indicated at 32 and 33, show the possibility of curving these contacting surfaces so as to provide an interlocking arrangement between the male and female members for the purpose of increasing their tensile contact over their full respective areas.

15 In Fig. 5, there is illustrated a modified form in which the pocket-like formation of the female member is constructed somewhat differently from that shown in Fig. 4, in that the bayonet-like structure 34 is formed opposite rib 18', and in which, from the bayonet-like structure, extends downwardly beneath the pocket formation, a spring element 35, for the purpose of rendering the unattached portion of the female member more resilient. In this construction, extension 36 of the bayonet arrangement is similar to the extension shown in Fig. 4, while in Fig. 6 this 20 extension is eliminated, and a spring element 37 is directly attached to the outer portion of bayonet formation 38.

25 Referring now to Figs. 7, 8 and 9, the male member shown in Fig. 7 consists of an upright portion 39, an outer horizontal portion 40 and an inner contacting portion 41, spaced from portion 40. The female member consists of an attaching portion 42, a raised continuation 43, a bayonet structure 44, which latter is constructed opposite to that shown in Figs. 4, 5 and 6, and which forms a left-hand pocket 45, at the right hand of which is again a reinforcing and limiting rib 46, from which extends a portion 47, terminating in an underslung spring element 48, arranged below the pocket structure.

30 In Fig. 9, extension 47 of Fig. 8 is eliminated and the resilient element 48' connects directly with locking rib 46'. In these modifications, the construction is somewhat simplified as far as the male member is concerned, but the female member retains all of its characteristics explained in connection with Figs. 4, 5 and 6, except that the construction is reversed.

35 Referring now to Figs. 10, 11 and 12, there is illustrated in Fig. 10 a male member 49, of a construction similar to that shown in Fig. 3, and a female member 50, resembling the structure shown in Fig. 5 in which, however, a bayonet formation 51 is employed which terminates in a 40 straight appendage 52. Associated with the bayonet structure and engaging the upright portion thereof is an individual corrugated spring element 53, adopted to render the pocket formation of the female member resilient.

45 In Fig. 11 a male member 54 is shown, which is also similar to that illustrated in Fig. 3, but reversed, and is in engagement with female member 55, in which the bayonet structure 56 is similar to that shown in Fig. 8. The rib or lock formation 57 is at the right and terminates in a short appendage 58. Engaging the upright portion of the bayonet structure again is illustrated an individual spring element 59, adapted to form a resilient cushion for the pocket-like 50 structure of the female member.

55 In Fig. 12, a female member similar to that illustrated in Fig. 11 is shown at 60, and provided with a rib formation 61, into which extends the upright portion of an individual resilient element 62, serving for the same purpose as that described in connection with Figs. 10 and 11.

60 For constructing my weather strip, I preferably employ metal which is not influenced by weather conditions, and which will not corrode and which will assure long life in constant use. However, any other suitable material, such as fibre or other composition matter, may be advantageously employed, in which case an individual resilient element such as shown in Figs. 10, 11 and 12, beneath the pocket structure is used.

65 From the foregoing description it will be perfectly clear that the male and female members telescope with one another and that their contacting surfaces are so designed as to keep the two members under constant tension and that the male member is locked within the pocket formation of the female member by the reinforcing rib illustrated, and that the sidewise movement of the male member is therefore limited by the rib. When an intense contact between the contacting surfaces is desired, the inner surfaces of the male and female members are curved as shown in broken lines in Figs. 3 to 6, whereby these members are further restrained against sidewise movement. Such contact over a large surface area assures perfect cooperation between the two members and results in long life and effectiveness of the device, irrespective of changes due to shrinkage or swelling of the objects to which they are secured and which they are intended to tightly connect against all weather conditions.

70 It is obvious that the male member or female member may be secured either to the stationary or movable portion of a window, depending upon the size thereof and its particular location. By the same token, it is not necessary to secure my device in the manner shown in Fig. 1, but it may be attached at either corner or on either side of the sash, as long as a suitable cooperation between female and male members is assured.

75 While I have shown specific constructions of my invention, it is quite evident that changes and modifications in the formation of the two members may be provided in order to meet various existing conditions and constructions of the objects to which they are to be attached and I therefore reserve for myself the right to make changes and improvements within my construction without departing from the broad scope of my idea, as set forth in the annexed claims:

I claim:

1. In a resilient weather strip construction, a resiliently mounted female member comprising a reinforcing rib formation and a pocket-like structure opposite thereto, said structure having a resilient, substantially bayonet-shaped retaining element consisting of spaced and looped surfaces, rendering it resilient, cushioning means extending from said female member and arranged substantially below said pocket-like structure, and a resilient male member comprising a substantially spirally looped structure in engagement with said pocket-like structure of the female member, the inner contacting faces of the male and female members being constructed and arranged so as to remain under constant tension relative to one another, said rib formation 70

75

of the female member serving as limiting stop for the sidewise movement of said male member.

2. In a weather strip for windows, adapted to be unaffected by either shrinkage or swelling of the window frame or sash, and being intended for limiting a lateral movement of a sash in respect to its frame, a female member having a substantially flat attaching portion, designed to be secured to the face of a window frame adjacent to the side of a sash, a rib formed from said attaching portion and projecting at substantially right angles towards such sash, a substantially

5 pocket-like convolution formed adjacent to, and with its open end towards one side of said rib, a male member, having a substantially flat attaching portion, adapted to be secured to one of the sash faces, a convolution formed at right angles to that attaching portion and tensionally and slidably interlocking with the convolution of the female member so that said rib of the latter member constitutes a stop against a sidewise movement of the male member.

10
